UNITED STATES PATENT OFFICE.

GEORGE A. SKELLY AND ARTHUR M. ANDERSON, OF OREGON, WISCONSIN.

DESIGN FOR A BADGE.

SPECIFICATION forming part of Design No. 25,245, dated March 10, 1896.

Application filed December 17, 1895. Serial No. 572,463. Term of patent 7 years.

To all whom it may concern:

Be it known that we, GEORGE A. SKELLY and ARTHUR M. ANDERSON, of Oregon, in the county of Dane and State of Wisconsin, have 5 invented and produced a new and original Design for a Badge, of which the following is a full, clear, and exact description.

Reference is to be had to the accompanying drawings, forming a part of this specification, 10 in which—

Figure 1 is a front view of a badge embodying our new design; and Fig. 2 a vertical section.

The leading features of our design consist 15 in the badge shaped to represent a tree-stump, the top of the badge inclined rearwardly and presenting the appearance of a cross-section of the stump, and the face of the badge be-

ing ornamented by a crossed hammer and ax and a wedge.

In detail the shape will be seen to present, in addition to the offset top, a semicircular form in cross-section and a forwardly-extended bottom edge, the crossed hammer and ax being represented on the lower portion of 25 the face of the badge, with the wedge below the same, and a series of stars below the said devices.

We claim—

The design for a badge herein shown and 30 described.

GEORGE A. SKELLY.
ARTHUR M. ANDERSON.
